(57) **CLAIM**

The ornamental design for a control module, as shown and described.

DESCRIPTION

FIG. 1 is a perspective view of a control module showing our new design, the portion in phantom lines in the figures forming no part of the claimed invention;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is another side view thereof.

The broken lines shown of the control module are for illustrative purposes only and form no part of the claimed design.
